INSULATED ELECTRICAL APPARATUS
 Daniel Berg, Churchill Boro, Pa., assignor to Westinghouse Electric Corporation, Pittsburgh, Pa., a corporation of Pennsylvania
 Continuation of application Ser. No. 260,794, Feb. 25, 1963. This application Mar. 2, 1965, Ser. No. 438,466
 3 Claims. (Cl. 336—57)

This application is a continuation of application Serial No. 260,794, dated February 25, 1963, now abandoned.

This invention relates to an electrical apparatus which includes a fluid means for cooling and insulating the apparatus. This invention also relates to a process for cooling and insulating an electrical apparatus.

It is well-known in the art to insulate an enclosed electrical apparatus with a liquid dielectric by immersing the apparatus in the liquid. The liquid functions to both cool and electrically insulate the operating electrical elements during use. There are certain disadvantages inherent in the use of a liquid dielectric for this purpose. One disadvantage is the necessity for employing large quantities of the liquid dielectric. Moreover, these liquid dielectrics require frequent attention and maintenance to prevent deterioration. Furthermore, there is the danger that if an electric arc develops within such a liquid dielectric, an explosion or fire may result, if the liquid dielectric is inflammable, or noxious and corrosive fumes may be emitted if the liquid dielectric is a halogenated compound.

Enclosed electrical devices which are insulated with various gaseous dielectric materials are also known in the art. However, it is generally necessary to use known gaseous dielectrics under considerable pressure in order to improve their dielectric breakdown strength. The use of these high pressures is frequently objectionable since exceptionally strong casings enclosing the electrical apparatus must be employed and great care must be exercised in gasketing and sealing of the joints in the casings. Any leak in the casing is usually fatal to the satisfactory operation of such an apparatus.

It is also known in the art to cool an electrical apparatus by flowing over the apparatus a thin layer or film of a liquid material, such as a liquid fluorinated organic compound. The compounds used are ones which, in the vapor phase, are dielectrics. When such a compound in the liquid state is passed over an electrical apparatus while in use, the apparatus is cooled by evaporation of the liquid and the resultant vapors of the compound provide insulation for the electrical winding. One of the physical properties essential to the widespread use of such a compound is high electric strength of the vapors. It is highly desirable that such a compound in the vapor state have a high electric strength at a pressure low enough so that the casing which encloses the electrical apparatus need not have particularly heavy walls to resist the pressure, and that the compound has a relatively low boiling point so that it will be converted to vapor at low temperatures in order that low cost solid insulation may be used.

It is an object of this invention to cool an electrical apparatus by flowing over the apparatus a liquid which effects cooling by evaporation, the evolved vapors of the liquid providing insulation for the apparatus.

It is another object of this invention to provide a method for cooling an electrical apparatus by contacting the apparatus with a liquid compound which, upon contact with the hot portions of the apparatus, vaporizes, thereby cooling the apparatus by evaporation, and the vapors serve to insulate the apparatus, the liquid being one which is converted to vapor at relatively low temperatures and the vapors having a high dielectric strength at relatively low pressures.

Briefly, the objects of this invention are obtained by providing an electrical apparatus, such as a transformer, comprised of a casing enclosing a source of heat. Thus, there may be disposed within the casing conductor members which are adapted to have an electrical potential developed across them and between which electrical discharges may occur, such as, for example, an electrical winding and a core. Such an electrical apparatus is one which, in use, develops heat. Provided within the casing is a supply of a liquid perfluoroalkyl derivative of SF₆. Specifically, the liquid may be C₄F₉SF₅, (C₄F₈)₂SF₄, or (C₃F₇)₂SF₄. During use of the electrical apparatus, the liquid is distributed over the electrical apparatus, for example, over the core and electrical winding. The apparatus is thereby cooled by evaporation of the liquid. The evolved vapors from the evaporating liquid provide an insulating gaseous atmosphere within the casing.

The compound C₄F₉SF₅, which may be used in the practice of this invention, has a molecular weight of 346, a boiling point of 70.5° C., a refractive index at 25° C. of 1.2701, a density at 25° C. of 1.839 and a dielectric constant of 2.068. This compound has a high vapor pressure. Because of the unique combination of physical properties of C₄F₉SF₅, it may be used as a coolant and insulating medium in an electrical apparatus at lower operating temperatures and pressures than compounds heretofore known such, for example, as SF₆ itself.

The compound (C₄F₈)₂SF₄ which may also be used in practicing the invention, has a molecular weight of 546, a boiling point of 154° C., a refractive index at 25° C. of 1.2943, a density at 25° C. of 1.903, and a dielectric constant of 1.951. It requires a higher operating temperature than C₄F₉SF₅ to attain the same pressure.

The compound (C₃F₇)₂SF₄ has a molecular weight of 446, a boiling point of 116° C., a refractive index at 25° C. of 1.2856, a density at 25° C. of 1.865, and a dielectric constant of 1.923.

These three perfluoroalkyl derivatives of SF₆ have been found to give outstanding results in the vapor cooling of electrical apparatus.

The invention will be more fully described with reference to the accompanying drawings wherein:

FIGURE 1 is a view, partly in section, through a transformer constructed according to the practice of this invention; and

FIG. 2 is a plot of breakdown voltages for the novel vapor-cooling compounds and for air as a function of pressure.

The drawings will be more fully explained hereinafter. In FIGURE 1, there is shown a transformer 10 having a core 11 and associated electrical windings 12 disposed within a sealed, gas-tight casing 13. The casing 13 may contain an insulating material 13a in order to maintain a near constant temperature and pressure within the transformer.

The core 11 is mounted on a grounded supporting member 14. Solid insulating barriers 15 are interposed between the windings 12 and the supporting member 14.

The windings 12 are provided with leads 16 which are connected to the bushings 17.

A sump 18 is situated in the lower portion of the casing 13. The sump 18 contains a supply of one of the novel liquids 19. The supply of this liquid is relatively small with respect to the total size of the casing 13. The liquid 19 while in the sump 18 is preferably maintained out of contact with the core 11 and the electrical windings 12. The liquid 19 is present in sufficient quantity to completely fill the casing 13 with vapor during the operation of the apparatus and still maintain a reserve of liquid.

A pump 20 is provided to circulate the liquid 19 through a conduit 21 to a spray device 22. The pump 20 is connected to the bottom of the sump 18 by means of the pipe 23. When the transformer is in operation, the liquid 19 which is delivered to the spray device 22 by means of the pump 20, is distributed over the core 11 and the electrical windings 12. The liquid when thus delivered distributes itself as a thin film over the core and the electrical winding and is evaporated, thereby cooling the core and the electrical windings and forming an insulating gaseous atmosphere within the casing. The cooling thus produced has been found to be very efficient and effective in maintaining uniform temperatures of the electrical elements. Evolved vapors of the compound which fill the transformer eventually flow to the condensing chamber 24 through the inlet 25 where the vapors condense. The condensed liquid then runs back into the transformer and to the sump 18 through the outlet 26. In some cases, it will not be necessary to use a condensing chamber if the walls of the casing 13 have sufficient area to dissipate the developed heat to the atmosphere. FIGURE 2 is a plot of the breakdown voltages for air and the vapors of the novel coolant liquids as a function of pressure. In determining the values plotted in FIGURE 2, the cell used was one in which the electrode comprised two 1-inch steel spheres spaced 0.6 cm. apart. Only A.C. voltages were used. In determining the values for the vapors of the coolant liquids, the cell was filled with about 10 cc. of liquid and then was placed in an oil bath and the temperature varied to obtain the desired vapor pressure. The pressure was measured with a mercury manometer attached to the cell. The results for air were obtained by filling the cell to various pressures with air. It is evident from FIGURE 2 that the vapors of the compounds have extremely high breakdown strengths as compared to air. Since they possess high electric strengths at relatively low pressures, there is no need for an exceptionally strong casing enclosing the electrical apparatus. Moreover, in view of the relatively low boiling points of the compounds, the operating temperatures of the electrical apparatus is much lower than is usually the case. Therefore, low cost materials such as pressboard and paper may be used as the solid insulation in the apparatus such as, for example, the insulation 13a in the casing walls and the material in the insulating barriers 15 shown in FIGURE 1.

The advantages of this invention are not limited to the transformer which is illustrated but may be applied to

other types of electrical devices such as for example switches, X-ray tube housings, capacitors, generators, cables, reactors, etc.

I claim as my invention:

1. An electrical apparatus comprising an enclosed casing, a source of heat disposed within said casing, a supply of liquid for dissipating the heat from said source of heat, said liquid being selected from the group consisting of $C_4F_9SF_5$, $(C_4F_9)_2SF_4$, and $(C_3F_7)_2SF_4$, and means for distributing said liquid over said source of heat to cool it by evaporation of said liquid.

2. An electrical apparatus comprising a sealed casing, an electrical device disposed therein, said electrical device having conductor members which are adapted to have electrical potentials developed thereacross and between which electrical discharges may occur, said electrical device developing heat during the use thereof; means for cooling said electrical device comprising a liquid selected from the group consisting of $C_4F_9SF_5$, $(C_4F_9)_2SF_4$, and $(C_3F_7)_2SF_4$, and means for distributing said liquid over said electrical device when in use, whereby cooling of said electrical device is effected by evaporation of said liquid, the vapors of said liquid providing for electrically insulating said conductor members of said electrical device.

3. An electrical transformer comprising a sealed casing, an electrical winding and core in said casing, a supply of a liquid selected from the group consisting of $C_4F_9SF_5$, $(C_4F_9)_2SF_4$, and $(C_3F_7)_2SF_4$ disposed in said casing, and means for distributing said liquid over said core and electrical winding, said liquid serving to cool said core and electrical winding by evaporation, the evolved vapors providing an insulating gaseous atmosphere within said casing.
